(57) **CLAIM**

The ornamental design for a retainer for a vibration motor, as shown and described.

DESCRIPTION

FIG. 1 is a front view of a retainer for a vibration motor showing my new design;

FIG. 2 is a rear view thereof;

FIG. 3 is a top plan view thereof;

FIG. 4 is a bottom plan view thereof;

FIG. 5 is a right side view thereof, the left side view being a mirror image thereof;

FIG. 6 is a perspective view when viewed from the front side thereof;

FIG. 7 is a perspective view when viewed from the bottom side thereof;

FIG. 8 is a cross-sectional view along lines 8—8 of FIG. 3;

FIG. 9 is a perspective view thereof, shown in environmental use; and,

FIG. 10 is another perspective view thereof, shown in environmental use.

The broken lines shown represent unclaimed subject matter and form no part of the claimed design.
